BARREL RIFLING MEANS

Edwin B. F. Schneek, Detroit, Mich.

Application June 3, 1940, Serial No. 333,469

6 Claims. (Cl. 90—28.1)

This invention relates to means for cutting rifle grooves in the barrels of firearms and has for its primary object to provide means capable of general use for this purpose, but which is more especially adapted for use in conjunction with barrels having tapered bores.

The tapered type of firearm barrel usually has a bore with a breech portion of uniform diameter, a muzzle portion of uniform diameter, and a tapered portion connecting the breech and muzzle portions. The projectile which is used with this type of barrel has circumferential vane-like portions, which fit the relatively larger diameter of the breech portion, and as the projectile passes through the bore the vane-like formations collapse radially inwardly to enable the projectile to pass through the small diameter muzzle portion. The purpose of the vanes is to increase the pressure area of the projectile for the attainment of higher projectile velocities.

Due to the varying diameter of the bore, rifle grooves cannot be formed by ordinary broaching methods, and an important object of this invention is to provide means including broach-like cutters and guide means therefor which functions to guide the cutters in a spiral path through the bore so that they cut a spiral groove in the wall of the bore, of uniform depth throughout the length of the bore. To this end, the invention provides a body having an external shape substantially identical to the shape of the bore. On this body is formed a spiral track (or possibly a multiplicity of tracks), and the broach-like cutters are adapted to travel in this track while the body is held stationary in the bore. As the cutters are drawn or otherwise caused to move through the track they cut a spiral groove in the surface of the bore.

Other objects and advantages will become more fully apparent as reference is had to the accompanying drawing wherein the invention is illustrated, and in which

Fig. 1 is a fragmental longitudinal cross section of a firearm barrel having a tapered bore,

Fig. 2 is a fragmental elevation of a cutter 45 guide,

Fig. 3 is a fragmental elevation of a second cutter guide,

Fig. 4 is a section illustrating the cutters,

Fig. 5 is a plan of the cutters,

Fig. 6 is a transverse section illustrating a cutter in the guide track, and

Fig. 7 is a section illustrating an alternative formation of the guide tracks.

In Fig. 1 there is illustrated a firearm barrel 1 55

having a bore 2 therein. The bore 2 has a breech portion *a* of uniform diameter, a muzzle portion *b* also of uniform diameter, but of a diameter smaller than the breech portion, and a tapered portion *c* connecting the breech and muzzle portions. The projectile used with this type of barrel is shown at 3, and as illustrated, has circumferential vane-like formations 4 of a diameter corresponding to the diameter of the breech portion. These vane-like formations collapse radially inwardly as the projectile passes through the bore.

Formation of rifle grooves in the bore 2 presents a problem due to its varying diameter, and the means hereinafter described is designed for this particular purpose. Although designed for this particular purpose, however, it will be understood that it is capable of other applications such, for example, as in the case of a bore having a uniform diameter.

In Fig. 2 there is illustrated a body 5 of a shape and size such that it is capable of fitting accurately within the bore 2. The surface of the body 5 is formed with a spiral groove track 6 adapted to receive cutters 7, as shown in Figs. 4 and 5. To cut a spiral groove in the surface of the bore 2, the cutters 7 are moved through the groove track while the body 5 is held in the bore. The cutters 7 comprise a multiplicity of hinged 20 connected bodies each having a cutting edge 7a. The cutting edges 7a vary in height as between different bodies, after the manner of broach cutters, so that as the cutters pass through the bore the first cutter takes a shallow cut, the second 25 a little deeper, and so on until the final cutter takes the final cut. The portions 7b of the cutters, as may be seen in Fig. 6, are shaped to engage the surface of the bore being grooved, laterally of the grooves, for maintaining the cutter bodies 7 flat within the groove track. These cutters may, for example, be pulled along the groove by a flexible wire-like element 10.

The groove track 6 is shown in Fig. 6 as having straight side walls, but they may be undercut, as illustrated at 8 in Fig. 7 for the reception of cutters having dovetail portions. Fig. 7 also illustrates the provision of a multiplicity of groove tracks on the body 9, and it will be understood from this disclosure that a multiplicity of grooves 50 6 may likewise be provided on the body 5.

When a single groove track 6 is employed, the body 5 is rotated a predetermined number of degrees between successive passes of the cutters, so as to form a multiplicity of parallel spiral grooves in the wall of the bore 2. Due to the varying

diameter of the bore the grooves so formed will have a larger land therebetween at the larger end of the bore than at the smaller end of the bore. For this reason a second body 5a is provided, of a shape and size identical to the shape and size of the body 5, and having a groove track 6a therein. At the larger diameter end of the body 5a the groove 6a is slightly offset from the position of the groove 6, which is illustrated on the body 5a by broken lines for purposes of comparison. As the groove 6a extends toward the smaller end of the body 5a it gradually approaches the position of the groove 6, and at the smaller end of the body it exactly overlies the position of the groove 6.

The body 5a is placed in the bore 2 in positions corresponding to the positions in which the body 5 was previously placed, and cutters are passed through the bore in each of the successive positions. In this manner spiral grooves are formed which are of greater width at the larger end of the bore than at the smaller end, thus making it possible to provide grooves and lands of equal width at every cross section of the barrel.

Although a specific embodiment of the invention has been illustrated and described, it will be understood that various changes may be made within the scope of the appended claims without departing from the spirit of the invention, and such changes are contemplated.

What is claimed is:

1. Means for cutting a rifle groove in the wall of a bore, comprising a body having a shape and size such that it fits snugly within the bore, said body having at least one spiral groove in the surface thereof, and a cutter received in said groove track and adapted to move therethrough with respect to said bore and said body while said body is held in the bore.

2. Means for cutting a rifle groove in the wall of a bore, comprising a body having a shape and size such that it fits snugly within the bore, said body having at least one spiral groove in the surface thereof, and a multiplicity of cutters connected in a series, said cutters being received in said groove track and being adapted to move therethrough with respect to said bore and said body while the body is held in the bore, each trailing cutter of the series being adapted to cut the wall of the bore to a greater depth than the cutter which it follows.

3. Means for cutting a rifle groove in a firearm barrel bore having a breech portion of larger diameter than its muzzle portion and a tapered portion connecting the breech and muzzle por-

tions, comprising a body having a shape and size such that it snugly fits within the different diameter portions of the bore, said body having at least one spiral groove track in the surface thereof, and a cutter received in said groove track and adapted to move therethrough with respect to said bore and said body while the body is held in the bore.

4. Means for cutting a rifle groove in a firearm barrel bore having a breech portion of larger diameter than its muzzle portion and a tapered portion connecting the breech and muzzle portions, comprising a body having a shape and size such that it snugly fits within the different diameter portions of the bore, said body having at least one spiral groove track in the surface thereof, a multiplicity of cutters connected in a series, said cutters being received in said spiral groove track, said cutters being adapted to be moved through said groove track while the body is in the bore, and each trailing cutter being adapted to cut the wall of the bore to a greater depth than the cutter which it follows.

5. Means for cutting a rifle groove in a tapered bore, comprising a cutter adapted to be moved through the bore, means for guiding said cutter in a spiral path which tapers at a rate corresponding to the taper of the bore as the cutter is passed through the bore, and a second guide means for guiding said cutter in a subsequent pass and through a spiral path which tapers at a rate corresponding to the taper of the bore and which is slightly offset from the first path at the larger end of the bore, the amount of offset of the second path decreasing as the diameter of the bore decreases.

6. Means for cutting a rifle groove in a firearm barrel bore having a breech portion of larger diameter than its muzzle portion and a tapered portion connecting the breech and muzzle portions, comprising a cutter adapted for movement through the bore, means for guiding said cutter in a spiral path which tapers at a rate corresponding to the taper of the tapered portion as said cutter passes through the bore, and a second guide means for guiding said cutter through a spiral path which likewise tapers at a rate corresponding to the taper of said tapered portion, said second path being uniformly offset from the first path in the breech portion, gradually approaching the first path as it extends toward the smaller end of the tapered portion, and coinciding with the first path in the muzzle portion.
